US00D683230S

(12) **United States Design Patent**
Crawford

(10) **Patent No.:** US D683,230 S
(45) **Date of Patent:** ** May 28, 2013

(54) **CONTAINER**(75) Inventor: **John C. Crawford**, Mahopac, NY (US)(73) Assignee: **Colgate-Palmolive Company**, New York, NY (US)(**) Term: **14 Years**(21) Appl. No.: **29/424,039**(22) Filed: **Jun. 7, 2012**(51) LOC (9) Cl. **09-01**

(52) U.S. Cl.

USPC ..... **D9/565**; D9/562; D9/575(58) **Field of Classification Search**USPC D9/682-694, 516-575, 434-436,
D9/447-450; 215/379, 382; 220/669-675

(57) **CLAIM**

The ornamental design for a container, as shown and described.

DESCRIPTION

FIG. 1 is a left front perspective view of a container showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines are included for the purpose of illustrating portions of the container that form no part of the claimed design.

1 Claim, 5 Drawing Sheets
